KARL KOLLER, OF BUDAPEST, HUNGARY

PRESSURE GAS PRODUCER

Original application filed July 8, 1924, Serial No. 724,876, and in Czechoslovakia and Germany July 14, 1923. Divided and this application filed August 16, 1929. Serial No. 386,355.

In pressure gas producers the mixture of steam and air required for gasifying the fuel enters the producer shaft through a distributing body which projects over the ash-pan. 5 The constructional forms made hitherto all have the disadvantage, that the mixture of steam and air is not utilized in the producer shaft in such a manner as is necessary for getting the best result from the fuel or for 10 producing a quality of gas corresponding to the fuel. Hitherto such distributors have been divided substantially into two groups. One of these groups comprises a short outlet pipe which is substantially the same size 15 as the supply pipe for the steam and air mixture which passes out through openings provided in the outlet pipe. These outlet openings are usually formed between conical rings which overlap one another like louvres 20 and which provide a total outlet for the mixture of steam and air of such a cross-sectional area that during the operation of the producer the difference in pressure between the fluid flowing within the interior of the 25 distributor and the pressure existing in the surrounding producer shaft will be only just sufficient to enable the mixture of steam and air to flow out effectively. When the producer is out of operation (i. e. when the 30 producer shaft is empty and closed by the ordinary water seal), the outlet openings in the distributor as hitherto constructed will form such communicating passages between the interior of the distributor and the empty 35 producer shaft that they will allow the mixture of steam and air to pass freely according to a law by which the flowing fluid shortly after leaving the distributor follows a practically vertical upward course. 40 In practice the proportions hitherto used between the total cross-sectional area of the outlet openings in the distributor and the internal cross-sectional area of the same lead to the following disadvantages: The outflow 45 of the mixture of steam and air from the openings in the distributor is determined, when the producer is in operation, by the resistance offered in the producer shaft by the fuel and thermochemical phenomena. As 50 explained above the fluid will pass almost vertically upwards through the outlet openings shortly after leaving the distributor when only the resistance offered by the surrounding air has to be overcome. This characteristic of the flow will not be substantially 55 changed when the producer is in operation, as the fluid will flow not in accordance with theory but in a direction determined by the places of least resistance in the shaft. (The more homogeneous the fuel, with the shaft 60 filled to the same height, the nearer will this direction of flow approximate in practice to the theoretical flow referred to above.) The consequence of this is that unburnt fuel 65 will pass through the producer. This resulted in the distributor in the form of a short pipe being abandoned and an ordinary grate being used extending almost up to the wall of the producer, so that the air could also have effective access to those parts of the fuel 70 situated in proximity to the wall of the producer and thus promote combustion of the fuel at the margin of the fuel bed. 75 The distributors belonging to the second group above referred to consist of chambers placed on the supply pipe and having a stepped conical shell the lowest part of which reduces the internal cross-sectional area of the producer shaft to such an extent that considerable resistance is offered to the passage 80 of clinker and ash through the producer. Such distributors have outlet openings which allow of the fluid obtaining a nozzle velocity (perforated grate) and the path of the air corresponding to such a velocity will follow 85 a parabola, it is a necessary condition for the proper operation of the producer that for each particle of air this path up to the producer wall will be of such a length that the air will be used up before reaching the producer wall. If this is not the case, the still unused air will flow upwardly along the producer wall, will cause marginal combustion of the fuel and combustion of the gas already 90 produced. Attempts have been made to prevent this marginal combustion by considerably raising the height of the fuel bed more particularly at the margins by means of special charging appliances. Marginal combustion however is not to be entirely avoided 95 100

by this means, this increase in the height of the fuel bed only temporarily suppressing it if the quantity of steam and air mixture blown through remains the same, and finally 5 a reduced output of the producer would be the only way out of the difficulty.

If such chamber-like distributors are provided with perforations not having the character of nozzles, these constructions suffer 10 from the disadvantages alluded to above to a still greater extent.

The present invention is based on the recognition of the fact that on the one hand the free annular space between the distributor 15 and the producer wall must be as large as possible for enabling the clinker and ash to pass through freely into the ash pan, hence the distributor must have the character of a short pipe as described above, while on the other hand the outlet openings must be in the wall of a cylindrical distributor and the ratio of the total cross-sectional area of these outlet openings to the internal cross-sectional area 20 of the cylindrical distributor must be such that parallel streams of fluid will result which follow the course of flat parabolas and have the required nozzle velocity, so that the fluid is already used up when it arrives at the 25 wall of the producer. As regards the desired degree of outlet velocity this arrangement has the further advantage, that the residual velocity of the fluid in the distributor from the velocity in the supply pipe is increased by the 30 nozzle action.

35 The invention is illustrated by way of example in the accompanying drawing wherein:

Figure 1 is a cross-sectional elevation 40 through a gas producer.

Figure 2 is a cross-sectional elevation of the distributor on an enlarged scale; and

Figure 3 is a cross-section of the distributor shown in Figure 2 on line 3—3 thereof.

Similar numerals refer to similar parts 45 throughout the several views.

The gas producer comprises a shaft 1 within which producer gas is generated, and having an annular skirt 2 which dips into the rotating ash-pan 3 which is filled with water 50 and moves the slag and ashes as they pass out of the producer shaft against a lateral scraper along which the slag and ashes are guided out of the producer.

The distributor is of cylindrical shape and 55 consists of separate rings 11 of uniform size arranged one above the other and spaced apart by means of ribs or the like so as to leave circumferential slots between them. The distributor is covered by a cap 12. The 60 fuel and the ashes are supported by the ash-pan 3. By building up the distributor from a number of rings of uniform size, the height of the distributor can be varied while maintaining its cylindrical character, so that the 65 combustion zone of the solid fuel bed in the

producer shaft can be adjusted to suit the conditions under which the producer is operated.

The invention also comprises the provision 70 of means for adjusting the effective total cross-sectional area of the nozzle outlet openings in order to enable the velocity of the mixture of steam and air flowing out from the distributor to be regulated so as to enable the incandescent or combustion zone proper 75 to be constrained to occupy a predetermined position to suit the actual conditions under which the producer is operated for the time being. By this means the regulation of the velocity can be adjusted so that the producer shaft is utilized directly as a low temperature 80 distillation chamber for the fuel. The preferred form of regulating means consists of a cylindrical valve arranged inside the distributor 85 will be described subsequently.

Another constructional form of the distributor has for its object to render the regulation 90 exceedingly simple, the mixture of steam and air introduced into the distributor and passing through it having its direction of flow reversed before entering the producer shaft, whereby the distributor is cooled and so protected from damage.

In the drawing the distributor 20 is formed 95 in a single piece in the wall of which are provided axial chambers 21 which are separated from one another by the material surrounding the outlet ports or openings 13 proper. The upper ends of all the chambers 21 are in open communication with the space inside the cap 12 into which the mixture of steam and air enters in the direction of the arrow 100 22. Within the distributor is a cylindrical slide valve 23 having openings 231 adapted to register with the openings 13 and which is closed at the bottom. The mixture of steam and air has its direction of flow reversed in the interior of the cap 12, after which it passes out into the producer shaft through 105 the nozzle outlets 13.

The mixture of steam and air thus cools the 110 wall of the distributor.

This is a division of my co-pending application Serial No. 724,876, filed July 8, 1924, 115 now Patent No. 1,728,684, September 17, 1929, for pressure gas producers.

I claim:

1. In a gas producer, a producer shaft 120 adapted to contain a solid fuel bed, an ash-pan, a short hollow blast distributor having a cap forming a top compartment, a plurality of vertical air and steam admission chambers located in the cylindrical wall of the distributor, and adapted to deliver air and steam to the top compartment, said wall of the distributor being provided with horizontal outlet air and steam ports located between the vertical chambers, a hollow cylindrical slide valve below the top compartment and 125 having openings adapted to register with the 130

outlet ports, and a bottom wall for closing the bottom of the slide valve.

2. In a gas producer, a producer shaft adapted to contain a bed of fuel, a hollow distributor having a cap and extending into said bed of fuel, a wall dividing said distributor into communicating sections, one of said sections having openings in the wall thereof communicating with the fuel bed, means for passing a gas-making fluid through said second-mentioned section into and through the first-mentioned section and through said openings into the fuel bed, and means for varying the effective area of said openings to change the velocity of the gas-making fluid entering into the fuel bed.

3. In a gas producer, a producer shaft adapted to contain a bed of fuel, a hollow distributor having a cap forming a top compartment extending into said fuel bed, a vertical gas-making fluid admission chamber located in the distributor and communicating with the cap, an additional chamber in the distributor communicating with the cap and provided with outlet openings positioned in the wall of the distributor, means for passing said gas-making fluid up through the first-mentioned chamber into said cap and down through said additional chamber, into and through said outlet openings, and means for varying the effective area of said outlet openings, and thus changing the velocity of the fluid passing therethrough into the fuel bed.

4. In a gas producer, a producer shaft adapted to contain a bed of fuel, a hollow cylindrical distributor having a cap forming a top compartment, vertical gas-making fluid admission chambers located in the distributor and communicating with the cap, an additional cylindrical chamber communicating with the cap and located in the distributor, said additional chamber containing a plurality of outlet openings positioned in the wall of the distributor and communicating with the fuel bed, means for passing said gas-making fluid up through one chamber, into said cap and down through the other chamber, into and through said outlet openings, and a cylindrical shell positioned in said additional chamber, said shell being provided with openings adapted to register with said outlet openings and being adapted to be rotated to change the effective area of the outlet openings and thus change the velocity of the gas-making fluid passing therethrough into the fuel bed.

In testimony whereof I affix my signature.
KARL KOLLER.
